WALDEMAR MEYER, OF WOODHAVEN, NEW YORK.

FASTENING MEANS FOR SHIPS' PLATES.

Application filed October 15, 1920. Serial No. 417,239.

To all whom it may concern:

Be it known that I, WALDEMAR MEYER, a citizen of the United States of America, residing at Woodhaven, county of Queens, and 5 State of New York, have invented new and useful Improvements in Fastening Means for Ships' Plates, of which the following is a specification.

This invention relates to devices adapted 10 for holding ships' plates in position to be riveted although not limited to such use.

Preparatory to riveting, the plates of a ship are usually secured together by bolts of the usual screw-threaded kind which are 15 inserted in certain of the rivet holes. The nuts being then applied and screwed home, the plates are drawn together. Rivets are then inserted in the holes not occupied by the bolts and set. The nuts are then un- 20 screwed, the bolts removed, rivets placed in the holes thus vacated, and set. The riveting of the plates together is thus completed.

Disadvantages of the procedure as above outlined are that the screwing up and un- 25 screwing of the nuts is a tedious and time consuming process; further, a long arm is required on the wrench for turning the nuts so that there will be sufficient leverage by which to pull the plates tightly together 30 which is necessary to secure a tight and secure structure, and in many situations in the constructing of a ship there is not sufficient room to permit the swinging of a sufficiently long wrench arm; further, the 35 threads on a large percentage of the bolts are battered at some stage of the proceeding and the bolts rendered useless. As a large percentage of the bolts employed for initially holding the plates of a ship's hull 40 together are thus destroyed by a single use and the quantity used in building a ship's hull is large, the destroyed bolts represent a considerable item of expense.

One object of the present invention is to 45 supply a fastening means which shall be readily applied and removed.

A further object of the invention is to 50 provide a fastening means which may be operated in a small space to forcibly draw the secured members together and also loosened to effect its removal.

A further object of the invention is to 55 provide a fastening means which shall not be liable to be injured but may ordinarily be used over and over again an indefinite number of times.

Other and ancillary objects of the invention will appear hereinafter.

In the accompanying drawings, which 60 illustrate the invention—

Fig. 1 is a side elevation of plates, such as those of a ship's hull, with the improved fastening means in position;

Fig. 2 is a section, on an enlarged scale, 65 through the device and plates;

Fig. 3 is a plan view of the seat for the wedge, showing the recess for receiving the wedge; and

Fig. 4 is a perspective view of the bolt. Referring to the drawings, the apparatus 70 comprises a bolt having a head 1 and a slot 2. This bolt may be formed by doubling upon itself a suitably formed piece as is indicated clearly in Fig. 4.

Adapted to be entered within the recess 75 in the bolt is a curved wedge 3. Placed about the bolt after the manner of a washer is a seat 4 adapted to bear against the work and to have the wedge bear upon it. The seat 4 has a recess 5 adapted to receive the 80 wedge and the bottom 6 of the recess is curved so as to fit the curved side of the wedge. Also the outer end of the recess 2 should be curved so as to fit the outer side of the wedge as shown clearly in Fig. 2. In 85 order to save metal and to reduce the area of contact with the plate, the side of the seat which is opposite the wedge is cut away at the center so as to form a concavity 7. A similar concavity 8 is formed upon the 90 wedge side of the seat and it will be seen from Fig. 2 that the seat is thinner upon the thick side of the wedge than upon the other side. It will be observed that the wedge seating surface is closer to the work 95 upon the side of the broad end of the wedge than upon the other side and consequently the making of the seat member thinner upon the former side renders the broad end of the seat more accessible in driving it 100 in and removing it, and furthermore a saving of metal is accomplished by this construction.

It will also be observed that the curved bottom 6 is an arc of a circle having its 105 central radius perpendicular to the plane of the outer surface of the seat. This construction of the seat renders the entry of the wedge into the recess in the bolt easier and brings the wedge into a position where its 110 end is more easily struck in operating the fastening.

It will now be seen that in order to draw the plates 9 and 10 together the bolt 1 is passed through registering holes in the plates. The seat 4 is then placed over the end of the bolt after the manner of a washer. The tip of the wedge is then inserted in the recess 2 in the bolt and its edge is entered within the recess 5 in the seat, the seat being so adjusted that the thin side is upon the same side of the bolt as the broad end of the wedge. The wedge may then be thrust through the recess until the device is fairly tight when the wedge may be driven home by striking it upon its broad end with a hammer when the plates will be drawn tightly together and securely held. The device may be disassembled by loosening the wedge which may be accomplished by driving it backwardly by striking it upon its tip. The wedge having been thus loosened, it may be withdrawn from the recess in the bolt and then the seat and the bolt may be removed and used again in a similar application.

While the invention has been illustrated in what is considered its best application it may have other embodiments without departing from its spirit and is not, therefore, limited to the structure shown in the drawings.

What I claim is:

1. The combination with a bolt, of a curved wedge cooperating therewith and a member adapted to bear against the work and having a curved seat for the said wedge.
2. The combination with a bolt, of a curved wedge cooperating therewith and a seat for said wedge adapted to bear against the work and having a recess for receiving

the wedge, said recess having a curved bottom forming a bearing surface for the curved side of the wedge.

3. The combination with a slotted bolt, of a curved wedge entered within said recess and a seat for said wedge adapted to bear against the work and having a recess for receiving the wedge, said recess having a curved bottom forming a bearing surface for the curved side of the wedge.

4. The combination with a bolt, of a curved wedge cooperating therewith and a seat adapted to bear against the work, the said seat being thicker at one side than at the other.

5. The combination with a bolt, of a curved wedge cooperating therewith, a seat adapted to bear against the work, the said seat being thicker at one side than at the other and the thin side being upon the same side of the bolt as the broad end of the wedge.

6. The combination with a bolt, of a curved wedge cooperating therewith and a member adapted to bear against the work and having a curved seat for the said wedge, the said member being thicker upon one side than upon the other and the said seat being an arc having its central radius at an angle to the axis of the bolt.

7. The combination with a bolt, of a curved wedge cooperating therewith and a member adapted to bear against the work and having a curved seat for said wedge, the said seat being an arc having its central radius at an angle to the axis of the bolt.

In testimony whereof I have signed this specification this 9th day of October, 1920.

WALDEMAR MEYER.
